MOISTURE INJECTOR-BASTER

Anthony W. Chiechi, 828 Di Fiore, Apt. 1,
San Jose, Calif. 95128

Filed Sept. 20, 1971, Ser. No. 182,277

Term of patent 14 years

Int. Cl. D7—02

U.S. Cl. D44—29 G

FIG. 1 is a top plan view of the moisture injector-baster showing my new design therefor;

FIG. 2 is a side elevation of FIG. 1;

FIG. 3 is a bottom plan view as seen from below in FIG. 2; and

FIG. 4 is an exploded perspective view of the moisture injector-baster with lid removed for purpose of illustration.

I claim:

The ornamental design for a moisture injector-baster, as shown and described.
